(57) **CLAIM**

The ornamental design for a hanger extender, as shown and described.

DESCRIPTION

FIG. 1 is a front elevated view of a hanger extender showing my new design.

FIG. 2 is a rear elevated view of the hanger extender.

FIG. 3 is a right side elevated view of the hanger extender.

FIG. 4 is a left side elevated view of the garment.

FIG. 5 is a top plan view of the hanger extender.

FIG. 6 is a bottom plan view of the hanger extender; and,

FIG. 7 is a perspective view of the hanger extender.

The broken lines are for illustrative purposes only and form no part of the claimed design.
